(57) **CLAIM**

The ornamental design for a game condition marker, as shown and described.

DESCRIPTION

FIG. 1 is a first perspective view of a game condition marker placed on a figurine, according to a first embodiment of the claimed design;

FIG. 2 is a second perspective view of the game condition marker, according to the first embodiment of the claimed design;

FIG. 3 is a front view thereof;

FIG. 4 is a rear view thereof;

FIG. 5 is a first side view thereof; and,

FIG. 6 is a second side view thereof.

The broken line showing of a figure is included for the purpose of illustrating portions of the “article” and forms no part of the claimed design.
